DESIGN FOR A TOY TELEGRAPH KEY

Herbert U. Dernehl, Milwaukee, Wis.

Application December 30, 1944, Serial No. 117,174

Term of patent 7 years

(Cl. D34—15)

To all whom it may concern:

Be it known that I, Herbert U. Dernehl, a citizen of the United States, residing at Milwaukee, in the county of Milwaukee and State of Wisconsin, have invented a new, original, and ornamental Design for Toy Telegraph Key, of which the following is a specification, reference being had to the accompanying drawing, forming part thereof.

Figure 1 is a front perspective view of a toy telegraph key, showing my new design; and Figure 2 is a rear perspective view thereof. The bottom of the toy telegraph key is plain. I claim:

The ornamental design for a toy telegraph key, as shown and described.

HERBERT U. DERNEHL.
